MEANS FOR SWINGING DOUBLE HUNG WINDOWS

Filed June 3, 1924

INVENTOR

Ralph L. Christenson

Harry Bowen
ATTORNEY

UNITED STATES PATENT OFFICE.

RALPH L. CHRISTENSON, OF SEATTLE, WASHINGTON.

MEANS FOR SWINGING DOUBLE-HUNG WINDOWS.

Application filed June 3, 1924. Serial No. 717,457.

The invention is a double hung window in which the sash may readily be swung inward when it is desired to clean the glass, re-putty, or replace the glass, or clean a full screen that may be placed on the outside of the window.

The object of the invention is to provide a means for swinging the sash of double hung windows inward.

10 Another object of the invention is to provide adjustable hinges upon which the sash may be swung inward which will also permit the sash to move upward and downward.

15 And a further object of the invention is to provide a removable section of the window frame so that it will be possible to swing one edge of the sash inward without requiring special sash.

20 With these ends in view the invention embodies a double hung window having adjustable means for pivotally supporting the lower sash, other means for pivotally supporting the upper sash when in the lower position, a removable stop between the sash 25 on one side, a removable section of the frame which is provided with clamping means for holding it in place, and other means for holding the ends of the window cords as the sash are being swung inward.

30 Other features and advantages of the invention will be seen from the following description taken in connection with the drawings, wherein:—

Figure 1 is a side elevation of a window 35 showing the devices as they would appear with the window in the normal position.

Figure 2 is a cross section through the window looking toward the hinges.

Figure 3 is a similar view looking in the 40 opposite direction.

Figure 4 is a sectional plan through the window.

Figure 5 is a detail showing one of the 45 disappearing supports for the lower sash.

Figure 6 is another detail showing the clamping means for holding the section of the frame in place.

In the drawings I have shown my device 50 as it would appear in use wherein numeral 1 indicates the window frame, numeral 2 the lower sash, and numeral 3 the upper sash.

The frame 1 is constructed in the usual manner with the stop or bead between the upper and lower sash and on the side of the frame which is opposite to that upon which the hinges are placed and which I have

indicated by the numeral 4, removable. Another section of the frame, which may be the guide for the lower sash, is also removable from the beveled cut indicated by the 60 numeral 5 to the lower end which is indicated by the numeral 6, and this removable section is indicated by the numeral 7. This section is provided with a knob 8 at its upper end and projecting pins 9 with heads 10, 65 which may be placed through openings 11 in plates 12 and then moved downward to the position shown in Figure 6 at which time the section 7 will be positively clamped against the side of the frame. It will be 70 observed that during this movement the pins 9 will move downward in slots 13 and the heads 10 will be held against the inner surfaces of the plates 12. The frame is also provided with hooks 14 and 15 which will 75 normally be covered by the section 7 and which may be used to hold the window cords from this side of the sash while the sash are swung inward.

The lower sash 2 is also made in the usual manner with a corner 16 of the beveled strip between the sash cut away as shown in Figure 4 to clear the stationary members of the upper sash hinges, and with inverted straight hooks 17 and 18 extending downward from one side of its face. These hooks will normally be out of engagement with the supporting members and when it is desired to swing the sash outward the supporting members, which I have indicated by the 80 numerals 19 and 20, may have their movable sections 21 and 22 moved outward to the position shown in Figure 5. However, before the members 21 and 22 are moved outward the sash 2 should be moved slightly upward until the members 17 and 18 are above the members 19 and 20 so that as the sash is 85 then moved downward, the downwardly extending portions of the hooks 18 will pass through holes 23 in the members 21 and 22.

The section 7 of the frame may then be removed by pulling outward and upward on the knob 8 so that the sash 2 will be free to swing outward as it is supported on the pivot members 19 and 20. As the sash moves out of the frame the knot 24 of the sash cord 25 may be removed from the opening 26 and placed under the hook 14 as indicated by the dotted line 27 in Figure 3. The sash will then be free to swing inward as far as 100 may be desired.

The upper sash 3 is also made in the usual

manner and provided with inverted straight hooks 28 and 29 on its face and at one side which will engage stationary sockets 30 and 31 when the sash is in the downward position. The sockets are provided with holes 32 into which the downwardly extending portions of the hooks will pass and when in the downward position the sash will be pivotally supported upon them. The removable stop 4 may then be removed, the sash swung inward, and the sash cord placed in the hook 15 in a manner similar to that hereinbefore described for the cord of the upper sash.

15 It will be understood that changes may be made in the construction without departing from the spirit of the invention. One of which changes may be in the location of the hinged members as it is understood that 20 they may be placed on either side of the frame or in any suitable position as may be desired; another change may be in the ex-

act design of the hinged members; and still another may be in the means for holding, or in the design of, the removable section of 25 the frame.

Having thus fully described the invention, what I claim as new and desire to secure by Letters Patent, is:—

30 In a supporting means for double hung windows, plates on the side of the window frame, U shaped members horizontally slideable in the said plates, said U shaped members having openings in their upper and lower sides, means for limiting the outward 35 movement of the said U shaped members and inverted straight hook shaped members extending downward from the side of a sash that is slideable in the said frame, said hook shaped members being adaptable to engage 40 the openings in the said U shaped members when the U shaped members are in the outward position.

RALPH L. CHRISTENSON.
